Louis A. Pelton, Baltimore, Md., assignor to Pompeian Olive Oil Corporation, Baltimore, Md., a corporation of Maryland

Application February 7, 1934, Serial No. 50,659

Term of patent 14 years

To all whom it may concern:

Be it known that I, LOUIS A. PELTON, a citizen of the United States, residing at Baltimore city, State of Maryland, have invented a new, original, and ornamental Design for a Bottle, of which the following is a specification, reference being had to the accompanying drawing, forming part thereof.

Figure 1 is a front elevation of a bottle showing
the design;

Figure 2 is a side elevation of a bottle showing the design; and

Figure 3 is a top plan view of a bottle showing the design.

I claim:

The ornamental design for a bottle as shown.

LOUIS A. PELTON.
